UNITED STATES PATENT OFFICE

CHARLES H. LOTTE, OF MASSILLON, OHIO, ASSIGNOR TO BYERS MACHINE COMPANY,
OF RAVENNA, OHIO, A CORPORATION OF MARYLAND

EXCAVATING MACHINE

Application filed August 17, 1928. Serial No. 300,231.

The invention relates to power excavating machines. In power excavating machines it is essential that mechanism shall be provided by which the dipper may be crowded in making an insertion in the ground. In some machines the hoisting line or cable is used to actuate the crowding mechanism and this can be accomplished only when the dipper is being hoisted. In other machines independent crowding of the dipper is accomplished by mechanisms including noisy gears, shafts, chains and sprockets.

One of the objects of the present invention is to provide an excavating machine with simple and efficient means by which crowding of the dipper may be accomplished, and thereby to eliminate the many disadvantages of previous mechanisms for the purpose.

Another object is to provide a machine so arranged that it may be readily converted into various forms such as a drag line, clam shell and a shovel or dipper excavator.

Another object is to provide a machine in which a power reversible crowding drum is utilized for two speed drag line work and also for moving the dipper and dipper arm or stick in and out.

Another object is to provide a machine with means by which the crowding cable may be automatically taken up.

Another object is to provide a machine with two drums on a common shaft by the use of which the machine is adapted for a variety of purposes.

The invention is illustrated in the accompanying drawings, in which Fig. 1 is a plan view of a machine constructed in accordance with the invention; Fig. 2 is a partly diagrammatic side elevation of the machine arranged as a dipper shovel excavator; Fig. 3 is a partly diagrammatic side elevation of a machine arranged for a drag line; Fig. 4 is an elevational view of a clam-shell bucket adapted to be used on the machine; Fig. 5 is a plan view of the operating mechanism of the machine, partly in section, illustrating the two drums mounted on a common axis; and Fig. 6 is a side elevation of the operating mechanism.

Referring more particularly to the drawings, the reference numeral 1 indicates a deck rotatably mounted upon a truck 2 which may be of any desired construction, but which is preferably of the caterpillar type as indicated. A suitable motor 3, which is here illustrated as an internal combustion engine, is mounted transversely of said deck to drive, through a belt or similar connection 4, a pulley 5 upon a jack shaft 6 journalled in frames 6a (see Fig. 5). All of the movable elements of the excavator are driven through the shaft 6.

Rotation of the deck

The jack shaft 6 carries at its end farthest removed from the pulley 5, a pinion 7 meshing with the gear 9 carried on the end of a swing shaft 10, the latter swing shaft being mounted parallel to the shaft 6 and journalled also in the frames 6a. Said shaft 10 mounts a pair of spaced clutches 11 and 11a, it being understood that one element of each clutch is secured to said shaft while another element of each clutch is rotatable with respect to said shaft. The rotatable element of the clutch 11 carries a bevel gear 12, and the similar element of the clutch 11a carries a bevel gear 13, and said gears are adapted to cooperate with a horizontally mounted gear 14 carried on a vertical shaft 15. The shaft 15 extends through the deck 1 and carries at its lower end a pinion 16 meshing with a gear 17 secured to the deck 1.

Presuming that the spindle of the engine 3 is rotating in a counterclockwise direction as viewed in Fig. 2, the jack shaft 6 and pinion 7 (see Fig. 6) will likewise be rotated in a counterclockwise direction to drive the gear 9 and swing shaft 10 in a clockwise direction. Thus it will be seen that, if the clutch 11 be engaged and the clutch 11a be disengaged, the bevel gear 12 will rotate the gear 14 in a clockwise direction as viewed in Fig. 5 to oscillate the deck 1 counterclockwise as viewed in said figure.

Similarly, if the clutch 11 be disengaged and the clutch 11a be engaged, the deck 1 will be rotated in a clockwise direction by co-operation of the bevel gear 13 with the gear 16.

14. Suitable means is provided for preventing the simultaneous engagement of the clutches 11 and 11a.

Locomotive mechanism

The jack shaft 6 carries a second pinion 8 adjacent the wheel 5, and said pinion meshes with a gear 28 on a drum shaft 29. The gear 28 meshes with a gear 30 secured to one member 31 of a suitable clutch mechanism mounted upon a shaft 21. The member 31 is rotatable with respect to the shaft 21, while another member 32 of said clutch is keyed to said shaft 21. The shaft 21 is known as the crowd and propelling shaft, since it serves to transmit power to the drum 36 for crowding the shovel into the work, and also, selectively, transmits power to the truck 2, both functions being described below.

20 The pinion 7 meshes with a gear 18 keyed to one member 19 of a second clutch mounted on the opposite end of the shaft 21. The member 19 is rotatable with respect to the shaft 21, while another member 20 of said clutch is keyed to said shaft. The usual band 22 is provided between the members 19 and 20.

It will be seen from the above that the shaft 21 may be rotated at either of two speeds, the one being dependent upon the ratio of the pitch diameters of the pinion 8 and the gear 30 and the other being dependent upon the ratio of the pitch diameters of the pinion 7 and the much larger gear 18. Adjacent the mid-point of said shaft 21 there is pinned to said shaft a member 25 provided with jaw clutch teeth at its opposite ends. On opposite sides of said member 25 there are sleeved on said shaft 21 bevel gears 23 and 24, each of said gears being provided with a hub extension formed with teeth adapted to cooperate with the teeth of said member 25. The operating means for said gears 23 and 24 is so arranged that the gears are reciprocated simultaneously, so that when the teeth of the hub extension of the gear 23 are engaged with the corresponding teeth of the member 25, the gear 24 is loose on such shaft 21, and vice versa.

Said gears 23 and 24 are in mesh with a horizontal gear 26 mounted upon a shaft 27 (see Figs. 2, 3 and 6) which extends through the deck 1 and carries at its lower end a bevel gear 27a meshing with a bevel gear 27b carried upon a horizontally mounted shaft 27c. A bevel gear 27d is carried at the opposite end of said shaft 27c and meshes with a bevel gear 27e mounted upon the axle 27f of one pair of drive wheels 27g for the tread 27h.

It will thus be seen that, presuming the engine 3 to be operating as before, if the clutch members 19 and 20 are clutched together, the shaft 21 will be rotated in a clockwise direction as viewed in Fig. 6, and will be so rotated at a very low speed. If, now, the teeth of the hub projection of the gear 23

be moved into mesh with the corresponding teeth on the member 25, the gear 26 and shaft 27 will be rotated in a clockwise direction as viewed in Fig. 5 to drive the excavator backward at low speed. If the gears 23 and 24 are moved to disengage the gear 23 and to engage the teeth of the hub projection of the gear 24 with the corresponding teeth of the member 25, the excavator will be driven forward at low speed. If the members 19 and 20 are disengaged and the members 31 and 32 are engaged, the gear 24 being engaged with the member 25, the excavator will be driven backward at its higher speed. And finally, if the gears 23 and 24 be returned to their first mentioned positions, the clutch members 31 and 32 being engaged, the excavator will be driven forward at its higher speed. It may be here noted that a brake drum 100 is mounted on the shaft 21.

Stick crowding and retracting mechanism

The drum shaft 29 above mentioned is journaled in the frames 6a parallel to the shaft 6. A drum 36 is loosely mounted on said shaft 29, and carries a gear 33 which forms one member of a clutch mechanism, the other member 35 of which is secured to the shaft 29 and carries an expanding band mechanism adapted to lock the members 35 and 33 together. A pinion 34 is bushed on the shaft 21 and may be moved into or out of mesh with the gear 32.

It will thus be seen that the drum 36 may be driven in a clockwise direction as viewed in Fig. 2 by engaging the member 35 with the gear 33, whereby said drum is driven directly from the shaft 29; or that said drum may be rotated in a clockwise direction at a lower speed by engaging the clutch members 31 and 32, sliding the pinion 34 into mesh with the gear 33, and disengaging the members 33 and 35, whereby said drum 36 is driven through the pinion 8, gear 28 (as an idler), gear 30, pinion 34, and gear 33; or that said drum may be driven in a counterclockwise direction by disengaging the members 31 and 32 and the members 33 and 35, engaging the members 19 and 20, and moving the pinion 34 into mesh with the gear 33, whereby said drum 36 will be driven at a much lower speed through the pinion 7, gear 18, pinion 34, and gear 33. A suitable brake mechanism 37 carried by said drum 36 is adapted to be operated by a suitably placed foot lever.

A cable 47 is wound over the top of said drum 36 and is carried forwardly beneath a sheave 49 and beneath a sheave 50 mounted intermediate the ends of the boom 45, and is carried upwardly and secured to the upper end of a reciprocable dipper stick 51. The cable 47 will hereinafter be termed the crowd cable, since it will be seen that such rotation of the drum 36 as will wind in the cable 47 will cause the dipper stick to be crowded

downwardly to insure a satisfactory cut. A second cable 48, hereinafter termed the reTRACTING or lifting cable, is wound under said drum 36 and extends beneath a second sheave 49 and is carried over a sheave 53 mounted on the same spindle with the sheave 50 and is secured to a point adjacent the lower end of the dipper stick 51. Quite obviously such rotation of the drum 36 as will wind in the cable 48 will cause the dipper stick 51 to be moved upwardly to retract the dipper 52 from the earth. It will thus be seen that clockwise rotation of the drum 36 will crowd the dipper into the earth and that counter-clockwise rotation thereof will retract the dipper from the earth.

Dipper elevating mechanism

A second drum 38 is loosely mounted upon the shaft 29 and has secured thereto one member 39 of a clutch mechanism, the other member 70 of which is secured to the shaft 29. The clutch mechanism 39—70 is practically identical with the clutch mechanism 33—35 and will here be described in some detail. Referring to Fig. 6, it will be seen that the disc 70 carries an expanding band mechanism 71. One end of the band is connected to one arm of a bell crank lever 72 pivotel at 72a to the disc 70. A link 73 is pivoted to the opposite end of said bell crank lever and to an auxiliary brake 77 which is connected to an operating lever (not shown). A radius arm 74 is connected to the opposite end of the clutch band and to the disc 70. An adjusting screw 75 is connected to the anchor end of the band and is supported in a boss 76 formed on the disc 70. The auxiliary brake drum 77 having a brake band on its periphery is mounted on the brake housing, one end being fastened to a side frame casting, and the other end being connected to the main operating lever, so that by slight movement of the lever, the power of the engine 3 is caused to actuate the expanding band mechanism 71 to lock the flange 39 to the shaft 29. A brake 37a similar to the brake 37 is carried by the drum 38 and is actuated by a foot lever (not shown).

A cable 55 is wound upon the drum 38, and extends outwardly and over a sheave 56 at the outer end of the boom and about a sheave 56b mounted in a housing 56c linked to the dipper 52. The anchor end of the cable 55 passes around a stationary sheave 56a, and is secured thereto.

Boom hoisting mechanism

A boom hoisting drum 40 is mounted on a short shaft 41 forwardly of the shaft 21 and carries a gear 42 in mesh with a pinion 42a bushed on a sleeve 42b which is keyed to the shaft 21. The pinion 42a and the sleeve 42b are formed with cooperating teeth, and said gear may be reciprocated to move its teeth

into and out of mesh with the teeth on said sleeve.

It will thus be seen that the drum 40 is driven from the shaft 21, and that it is capable of all of the flexibility of direction and speed of rotation of which the shaft 21 is capable.

A cable 43 is wound on said drum 40 and passes over a sheave 44 mounted on the frame of the excavator and about sheaves 44a and 44b on the boom 45. The cable 43 is adapted to be reeved six strands. In accordance with usual practise, the boom 45 is pivoted to the deck 1 as at 46, so that, when the drum 40 is rotated to draw in the cable 43, the outer end of the boom 45 is elevated. A suitable brake is, of course, provided for the drum 40.

Drag line bucket operation

In Fig. 3, the machine is illustrated as adapted for drag line bucket work. A boom 57 of slightly different construction from the boom 45 is substituted for said latter boom, said boom 57 being pivoted at 46. The cable 43 is, as before, wound on the drum 40, and reeved through sheaves at the point of the boom. The cable 55 is passed over a sheave 56 at the point of the boom and connected to a drag line bucket 58 to support the same. A cable 59 is secured to the upper leading edge of the bucket 58 and passes around a sheave 60 suitably secured to the cable 55 above the connection of the latter with said bucket 58. A link 61 of suitable form is secured to the leading edge of the bucket 58 and carries at its outer end an eye 61' through which the cable 59 extends. The cable 59 then passes through a fair lead 62 and is wound upon the drum 36, taking the place of the cable 47. It will thus be seen that, if the members 33 and 35 are clutched together, the cable 59 will be drawn in at a relatively high speed; and that, if the members 33 and 35 are disengaged and the members 31 and 32 are engaged, the pinion 34 being moved into mesh with the gear 33, the cable 59 will be drawn in more slowly.

If it is desired to get a still slower drag for the bucket 58, the cable 59 may be wound beneath the drum 36, and the members 19 and 20 may be clutched together whereby the drum 36 will be driven through the pinion 7, gear 18, pinion 34, and gear 33.

Clam shell bucket operation

Fig. 4 shows an elevation of the outer end of the boom 57 together with a clam shell bucket 63 and its connections. In this modification, a cable 64 is connected to the hoisting and closing mechanism 63a of the bucket 63 and passes over the sheave 56c at the point of the boom 57 on the same shaft with the sheave 56. The cable 64 is led down the boom 57 and is wound on the drum 38. A second cable 55a is connected to the bucket 63, passes over the sheave 56 and is wound on the drum

36 to serve as a holding line. The drum 36 in this case is lagged to the same diameter as the drum 38 in order to permit the two drums to be operated with the same line speeds. An automatic spring take-up device can be arranged on the clutch 35 on the drum 36 to insure the hauling in of the holding line 55a while the hoisting line 64 is being drawn in. Such an arrangement will require only one lever for operating the drum 38, and separate foot levers for the brakes 37 and 37a.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a power excavator, the combination of a frame, a turntable mounted on the frame, a boom extending from the turntable having a dipper stick and dipper, a main driving shaft, a drum supporting shaft, an auxiliary shaft, two sets of gears of different ratios engaging the main shaft and adapted to be selectively connected to the auxiliary shaft for driving the latter shaft in opposite directions at different speeds, a gear of one of said sets being secured to the drum supporting shaft for continuous rotation thereof by the main shaft, two drums loosely mounted on the drum supporting shaft, each having a clutch mechanism for locking the drum to the said shaft, a gear secured to one of the drums and a clutch pinion on the auxiliary shaft adapted to be engaged with the drum gear to cause the auxiliary shaft to rotate the said drum selectively in opposite directions.

2. In a power shovel machinery assembly, a jackshaft, means for applying power thereto, a drum shaft, a swing shaft, a crowd and propelling shaft, mutually engaging gears on said shafts, frames giving bearing support to the ends of said shafts, means for driving said drum shaft by said gears directly from said jackshaft, means for driving said crowd and propeller shaft in one direction and at one speed directly from said jackshaft, and in opposite direction and at a different speed from said drumshaft, and means for transporting the assembly by power applied through said crowd and propeller shaft in either forward or reverse direction at either speed.

3. In combination with apparatus of the class described comprising traction means, a turntable supported thereby, material-moving means supported by said turntable, and a prime mover mounted on said turntable, a machinery assembly comprising a jackshaft, means for transmitting power thereto from said prime mover, a crowd and propelling shaft, gears on said last-named shaft, gears

on said jackshaft engaging said gears, a drum shaft and a gear thereon engaging both said jackshaft, gear and said crowd and propelling shaft, gear, means including all said gears for driving said crowd and propeller shaft either from said jackshaft or from said drum shaft, and means for driving said traction means from said crowd and propeller shaft.

4. In combination with apparatus of the class described comprising traction means, a turntable supported thereby, material-moving means supported by said turntable, and a prime mover mounted on said turntable, a machinery assembly comprising a jackshaft, means for transmitting power thereto from said prime mover, a drum shaft, a crowd and propelling shaft, gears on said last-named shafts, gears on said jackshaft engaging said gears, means for driving said crowd and propeller shaft either from said jackshaft or from said drum shaft, means for driving said traction means from said crowd and propeller shaft, a plurality of drums on said drum shaft selectively adapted for free rotation relatively thereto or for engagement therewith, means for selectively driving one of said drums from said crowd and propeller shaft, and operative connections between said drums and said material-moving means.

5. In combination with apparatus of the class described comprising traction means, a turntable supported thereby, material-moving means supported by said turntable, and a prime mover mounted on said turntable, a machinery assembly comprising a jackshaft, means for transmitting power thereto from said prime mover, a drum shaft, a swing shaft, a crowd and propelling shaft, gears on each of said three last-named shafts, gears on said jackshaft engaging said gears, means for driving said crowd and propeller shaft either from said jackshaft or from said drum shaft, means for driving said traction means from said crowd and propeller shaft, a plurality of drums on said drum shaft selectively adapted for free rotation relatively thereto or for engagement therewith, means for selectively driving one of said drums from said crowd and propeller shaft, operative connections between said drums and said material-moving means, means adjacent said crowd and propeller shaft and actuatable therefrom for changing the position of said material moving means relatively to said turntable, directionally selective means on said swing shaft for turning said turntable.

Signed by me this 9th day of August, 1928.
CHARLES H. LOTTE.
